UNITED STATES PATENT OFFICE

CHARLES E. SANDERS, OF LA PLATA, MISSOURI

BEEHIVE BROOD FRAME

Application filed March 4, 1930. Serial No. 433,134.

This invention relates to improvements in brood frames for beehives.

The primary object of the present invention is to provide an improved type of frame into which a comb foundation may be easily and quickly placed and in which it will be firmly held against buckling or warping.

In certain types of frames at present in use it is extremely difficult to place the foundation or starter in position without pulling or breaking the same and this is particularly true if the frame has been previously used so that it is covered with wax. After a frame has been used it must be carefully gone over and the grooves in which the comb foundation edges are placed must be scraped out before a fresh foundation can be put into position. This is troublesome and time consuming and if the grooves are not thoroughly cleaned it is more than likely that the foundation will be damaged when placing it in position.

With the frame embodying the present invention the top and side bars thereof are made in two sections between which edges of the comb foundation are securely clamped. When the frame is removed after the formation of a comb thereon the foundation can be easily cut away and the remaining pieces between the separable portions or bars of the frame easily and quickly removed by scraping and if all of the remaining bits of the foundation are not completely removed this will in no way interfere with the proper placement of a new foundation in the frame. After the foundation has been placed in position it will be firmly held and cannot twist or warp.

Another object of the invention is to provide a beehive brood frame of the hanging type in which the members employed for holding together the units making up the top and side bars of the frames are arranged to abut one against the other and thus serve to properly space the frames in the hive.

The invention will be best understood from a consideration of the following detailed description taken in connection with the accompanying drawings forming part of this specification, with the understanding, however,

that the invention is not confined to any strict conformity with the showing of the drawings but may be changed or modified so long as such changes or modifications mark no material departure from the salient features of the invention as expressed in the appended claims.

In the drawings:

Figure 1 is a view in side elevation of the frame embodying the present invention.

Figure 2 is a view in end elevation of a pair of the frames showing the manner in which they are spaced when in use.

Figure 3 is a sectional view taken on the line 3-3 of Figure 1.

Referring more particularly to the drawing wherein like numerals of reference indicate corresponding parts throughout the several views, the numeral 1 indicates generally the improved frame embodying the present invention. This frame comprises the usual top bar 2, side bars 3 and bottom bar 4. As shown in Figures 2 and 3 the side and top bars of the frame are each made up of two members. The two members comprising the top bar being indicated by the numerals 5 while each of the two members comprising the side bars 3 are indicated by the numerals 6. Each end of the top bar 2 is cut away transversely at the lower corner to form the supporting shoulder 7 by means of which the frame is suspended upon suitable supports within the beehive. Inwardly slightly of each cut away end of the top bar 2 each member 5 of the top bar has a recess 8 cut in the outer face thereof, the inner wall of each recess being inclined inwardly from the bottom to the top giving to the bar 2 in cross-section the appearance of a dovetail as shown in Figure 3.

The confronting faces of the members 6 making up each of the side bars 3 are also cut inwardly as indicated at 9 with the inner face of the cut inclined outwardly toward the adjacent face of the member so that there is thus formed in the upper end of each side bar 3 a dovetail recess as shown in Figure 3 for the reception of one dovetailed portion of the top bar 2.

At their lower ends each of the members

2 making up the side bars 3 of the frame are cut away to form the dovetail recesses 10 which open downwardly from the ends of the members and in each of these recesses there 5 fits one end of the bottom bar 4 which is of dovetailed cross-section throughout as shown.

Each of the side members 3 of the frame has passed therethrough a pair of holding bolts each of which is indicated by the numeral 11 and the bar 2 has a wood screw or other suitable holding element threaded thereinto intermediate its ends as indicated at 12, these bolts and the screw, of course, acting to secure the members making up the 10 top and side bars in assembled relation as will be readily understood and in addition to this they cause the members of the top and side bars to grip the edges of a comb foundation disposed therebetween. The bolts 15 11 holding the members of the side bars 3 together also cause the side bars to maintain a firm grip upon the top and bottom bars 2 and 4 thus giving a strong rigid frame which cannot be twisted out of the square and 20 which cannot be easily broken.

In placing a comb foundation in the frame 1 the nuts upon the bolts 11 and screw 12 are removed so that the frame top and side bars may be divided into two portions, the lower 25 members retaining the bolts projecting upwardly from the surface upon which the frame may be laid. The foundation which is indicated by the numeral 13 is then placed in position upon the members carrying the holding bolts after which the associate members 30 are placed in position upon the first mentioned members to complete the formation of the top and side bars of the frame, the nuts being replaced upon the holding bolts and drawn up tightly thereon against the adjacent members to secure the members of the bars together and to cause them to grip the edges of the foundation 35 therebetween.

40 As shown in Figure 2 the bolts employed for holding the members of the side bars together project beyond the bars in which they are positioned so that when the frames are placed in a hive the ends of the bolts 45 will come into contacting relation and thus suitably space the frames.

These contacting bolts hold the frames apart so that the wax of the combs will not cause the frames to adhere one to the other, 50 the only points where adherence may occur being between the contacting ends of the bolts. As these small surfaces may be readily separated it will be seen that the removal of any one of the frames from the hive may 55 be effected without difficulty and without jarring the frames or injuring any of the bees thereon or on adjacent frames.

Having thus described my invention, what I claim is:

60 1. A brood frame for beehives having top,

bottom and side bars, said top and side bars only being longitudinally divisible to form two portions between which the edges of a comb foundation may be secured and means for securing the ends of the bottom bar between the sections of the side bars.

2. A brood frame for beehives having top, bottom and side bars in which the top and side bars only are each longitudinally divided to form coacting members between which the edges of a comb foundation may be placed, and means for securing the members of the top and side bars in gripping relation against an interposed edge of a foundation body the said bottom bar being longitudinally intersected by the plane occupied by the abutting faces of the members of the top and side bars.

3. A brood frame for beehives having top, bottom and side bars in which the top and side bars are each longitudinally divided to form coacting members between which the edges of a comb foundation may be placed, and means for securing the members of the top and side bars in gripping relation against an interposed edge of a foundation body, said top bar being extended beyond the side bars and formed to facilitate the proper suspension of the frame in a hive.

4. A brood frame for beehives having top, bottom and side bars in which the top and side bars are each longitudinally divided to form coacting members between which the edges of a comb foundation may be placed, and means for securing the members of the top and side bars in gripping relation against an interposed edge of a foundation body, said securing means of each frame being of a character to coact with the securing means of an adjacent frame to properly space a plurality of the frames when in position in a hive.

5. A brood frame for beehives having top, side and bottom bars, said top and side bars being longitudinally divided to form of each a pair of coacting members between which the edges of a comb foundation may be gripped, means for drawing the members of the top and side bars firmly together to grip a foundation, and means for forming a rigid joint between the top and side bars comprising a dovetailed recess formed in the upper end of each side bar to receive therein a portion of the top bar formed in cross-section to fit the recess.

6. A brood frame for beehives, comprising top, bottom and side bars, said top and side bars being longitudinally divided to form each into a pair of coacting members, said top bar adjacent each end being formed to present a dovetail cross-sectional design, said bottom bar being of dovetail cross-sectional design at each end and said side bar members having their confronting faces cut away to form each end of each side bar with a dove-

tail recess therein for the reception of a similarly formed portion of the top or bottom bar, and means connecting the members of the top and side bars for drawing the same together in gripping relation upon an interposed edge of a comb foundation.

5 In testimony whereof I hereunto affix my signature.

CHARLES E. SANDERS.
